UNITED STATES PATENT OFFICE.

THEODORE FANTA, OF CHICAGO, ILLINOIS.

UNDERSHIRT.

No. 877,416.

Specification of Letters Patent.

Patented Jan. 21, 1908.

Application filed September 24, 1907. Serial No. 394,286.

To all whom it may concern:

Be it known that I, THEODORE FANTA, of Chicago, in the county of Cook and State of Illinois, have invented certain new and useful Improvements in Undershirts; and I do hereby declare the following to be a full, clear, and exact description of the invention, such as will enable others skilled in the art to which it appertains to make and use the same.

My invention relates to undershirts for infants, the object being to provide a shirt having a double lap in front, with improved means for securing the free ends of the two laps to the body of the shirt thereby providing a close fit and preventing the lower end from working up on the abdomen.

A further object is to dispense altogether with pins and buttons and provide securing means which will permit the shirt to be adjusted to the body of the wearer, and amply protect the chest and abdomen.

With these objects in view my invention consists in the details of construction as will be more fully described and pointed out in the claims.

In the accompanying drawings, Figure 1 is a view of the shirt open. Fig. 2 is a view with the inner flap closed and secured, and Fig. 3 is a view showing the outer flap closed.

1 represents the back or body of the shirt, provided with the usual neck band and sleeves, and 2 and 3 are the inner and outer flaps respectively, both formed integral with the body 1. The inner flap constitutes the inner front of the shirt, and is of a width sufficient to cover the front of the body and is provided at its free edge with the tape 4 stitched to the front edge of the flap, at about the median line of the abdomen, the two ends 5 of the tape being turned at right angles and of sufficient length to pass through the holes 6 in the body and be tied together outside the shirt. The section of the shirt having holes 6 therein is on a line with the under side of the right sleeve and is reinforced by the tape 7 stitched to the inner face of the body and projecting beyond the holes.

50 The outer flap 3 is adapted to fold over and rest on the inner flap, thus providing double thickness of material over the chest and abdomen, and is provided on the inner

surface of its free edge with a tape 7^a stitched thereto, the ends of the tape being free. The 55 body of the shirt is also provided on a line under the left sleeve with a tape 8 stitched to the outer surface of the body, the said tape 8 having two free ends which when the outer flap is folded over the inner flap, conform in position to the free ends of tape 7^a to which they are tied. The upper and lower ends of the two tapes 7^a and 8 are so located 60 as to come respectively above and below the abdomen, thus permitting the shirt to closely 65 fit the body without undue pressure on the abdomen, the lower ends of the two tapes, also operating to prevent the shirt from creeping up on the abdomen.

By reinforcing all that part of the shirt and 70 flaps between the free ends of the tapes or braids, I take the strain from the shirt proper, hence the tendency to tear at the points subjected to strain is largely overcome.

With this construction I dispense entirely 75 with buttons and pins and provide a shirt which can be put on like a coat and so secured and held in place, as to fully protect the body of the wearer.

Having fully described my invention, what 80 I claim as new and desire to secure by Letters Patent, is,—

1. As a new article of manufacture, a shirt comprising a back or body and two flaps, the inner flap being provided at its free end 85 with a reinforcing tape having free ends adapted to be passed through holes in the body of the shirt and means for securing the free edge of the outer flap to the body.

2. As a new article of manufacture, a shirt 90 comprising a back or body and two flaps, the inner flap being provided at its free edge with a reinforcing tape having free ends adapted to be passed through holes in the shirt, and the outer flap provided at its free edge with 95 a reinforcing tape having free ends adapted to be secured to the free ends of a reinforcing tape secured to the body of the shirt.

In testimony whereof, I have signed this specification in the presence of two subscribing witnesses.

THEODORE FANTA.
